SAFETY ANCHOR

Application filed January 9, 1930. Serial No. 419,726.

The invention relates in general to a window cleaner's safety anchor and to the combination of the same with a multiple part building construction unit such as a window casing.

It is a usual practice in mounting anchors of this type in position to extend them more or less into the masonry and similar structural parts in order to insure a security of connection. Under some circumstances it is difficult, if not impossible, to drill into old masonry structures in order to mount the anchors in place and under other circumstances it is difficult to attain sufficient purchase on the masonry structure to effect a positive securing of the anchor in the desired place. To meet this difficulty it has been suggested to secure the anchor to an exposed element of the window frame or other structural unit distinct from the masonry, but this face mounting of the anchor has not been a safe procedure as abnormal strain on the anchor would be very apt to either break the anchor away from the frame or carry with it the particular portion of the frame to which it was attached. It has also been suggested to provide prongs which are designed to be driven into the face portion of wooden frames. Such structure is of no value in the case of frames other than wood or where for any reason it is not desirous to mutilate the wooden face and further a different size anchor has to be provided for frames or similar supporting parts of different dimensions.

The primary object of the invention is to provide a simple form of casting which forms the anchor proper with any suitable and conventional form of carriage bolt, and which assembly anchor and bolt, can be readily applied to window frame structures, and the like, without necessity of mutilating exposed surfaces; which will securely position the anchor in place with a single fastening bolt which can be accommodated to frames of different depths simply by selecting the proper size of bolt and which will tend additionally to secure together the parts of

the frame structure to which it is attached and thus minimize the tendency to separate the parts of the same or other structure to which it is attached.

Another object of the invention, and specifically referring to the anchor as an article of manufacture per se, is to provide for maximum strength and rigidity with the use of the least possible amount of metal and to dispose the metal in such way as to cause one part to brace the other and to provide a rugged form of harness engaging post which will facilitate an easy engagement therewith of the harness and which will tend to brace the supporting portion of the anchor at the place where it is most liable to be weak.

Broadly, the invention is attained by providing a main attaching plate which carries the post as an integral part projecting therefrom and which plate is secured in position by means of a single bolt which preferably has a length sufficient to pass through the several parts which go to make up the frame and in this way act not only to secure the anchor in place but to tie the structural parts parts to each other, and to the anchor. In order to defeat any tendency of the anchor to turn about the single bolt as a pivot, the disclosure features one or more facing flanges coacting with the main plate to form an angle structure and in its engagement with the mounting supporting structure to defeat any tendency of the anchor to rotate about the bolt.

Various other objects and advantages of the invention will be in part obvious from an inspection of the accompanying drawing and in part will be more fully set forth in the following particular description of one form of mechanism embodying the invention, and the invention also consists in certain new and novel features of construction and combination of parts hereinafter set forth and claimed.

In the accompanying drawing:

Fig. 1 is a view partly in horizontal section through the part of a conventional form of window frame adjacent the window guides, showing a preferred embodiment of the invention mounted thereon;

Fig. 2 is a plan view looking down upon the anchor shown in Fig. 1 with the bolt element removed; and

Fig. 3 is a view in front elevation of the anchor looking at the same from the right side of Fig. 1.

In the drawing and first referring to the showing in Fig. 1, there is disposed the usual masonry structure 10. Fitted conventionally in the masonry is a wooden window frame 11 certain parts 12, 13, 14 and 15 of which are illustrated to show the function of the bolt hereinafter described to defeat any tendency for abnormal strains on the anchor to separate the parts of the frame. Forming part of the frame structure is the facing strip 16 usually fastened in place temporarily by a couple of nails and which strip can be readily removed to permit the installation of the anchor herein featured and afterwards replaced to preserve the finish of the frame.

Referring particularly to the anchor feature of the disclosure there is illustrated a one piece integral casting comprising essentially a main plate 17 which is relatively wide as shown in Fig. 2 to obtain the requisite area of engagement with the face 18 of the outer supporting frame part or member 12. In the illustrated showing this plate 17 is flat to fit the flat face 18 which constitutes the majority of such faces in conventional window frame constructions. In some limited number of cases the face 18 is not flat but is curved in different ways and it is within the scope of this disclosure to design the plate 17 so as to conform to the configuration of the surface 18 with which it engages.

It is a feature of this disclosure that the anchor is secured in place mainly by a single fastening bolt and to accommodate this bolt the plate 17 is provided with a non-circular bolt hole 19. A long bolt 20 has a non-circular head portion 21 fitted into the hole 19 so as to prevent rotary movement between the bolt and the anchor when the bolt nut 22 is turned on the opposite exposed end 23 of the bolt. The bolt extends through the several parts 12, 13, 14 and 15 and acts not only to hold the plate 17 in firm engagement with the surface 18 but also acts to secure these frame parts together. In such constructions, the nut 22 is usually accessible without mutilating or dismantling any part of the frame structure and the long bolt not only adds structural material to the anchor itself but braces the anchor in a direction at right angles to the plane of the plate 17. The outer edge of plate 17 is shown to be straight as indicated at 24 and depending integrally from this plate 17 is a pair of face flanges 25 and 26 extending at right angles to the plate 17 and coacting therewith to form an angle member as viewed in side elevation in Fig. 1. The

face flanges 25 and 26 abut and engage the face 27 constituting the front edge of the supporting member 12 and act in their engagement therewith to prevent any tendency of the plate 17 from rotating with the bolt about the axis of the bolt.

It is suggested that fastening means in addition to the long bolt may be used where there is no objection to mutilating the surface 27 and accordingly the flanges in the device illustrated are each provided with a screw hole 28 into which may be inserted wood screws 29 passed therethrough and into the supporting member 12 in offset relation on opposite sides of the bolt 20.

Extending outwardly from the main plate 17 at its straight edge 24 is a harness engaging post 29 projecting integrally from the top of the plate 17 and from the portion thereof between the flanges 25 and 26. The post is somewhat curved and terminates at its outer end in a square head 30. The post is gradually increased in cross sectional area from its mid-length towards the main plate 17 and rounds into this plate as indicated at 31, 32 and 33 to form maximum strength at the end attached to the plate. The outer side of the post is concaved as shown at 35 and rounds from the head 30 into the plane containing the flanges 25 and 26. In order to lighten the structure at a point where material is not needed it is suggested that the flanges 25 and 26 be of no greater width than is necessary to accommodate the screws and thus a space 34 will be left in the facing flange.

The anchor is mounted in place by removing the facing strip 16 and drilling a bolt hole through the parts of the casing where the anchor is to be located. The anchor is then disposed in position with bolt hole 19 in alignment with the drilled bolt hole and with the flanges engaging the outer face 27 of the support. A bolt 20 of the proper length is then passed through the hole 19 and its nut 22 drawn up and tightened until the parts are rigidly secured in place after which strip 16 may be replaced and the device is ready for use. In those cases where it is desired to pass screws 29 through the face flanges such screws may be turned into place thus providing additional security to the structure as a whole.

It is within the scope of the disclosure to omit the recess 34 between the flanges 25 and 26 and to use a single flange instead of the two flange structure illustrated. It is also within the scope of the disclosure to provide two spaced apart posts in place of the single post illustrated following a known construction in this respect.

By means of a device of the type disclosed there is provided a positive, secure connection between an anchoring device and a support even where the support is made up of

structural elements which would ordinarily have a tendency to separate when strains were placed upon the anchor. The anchor can be mounted in position without materially mutilating the supporting structure and in fact the fastening means are limited to a single bolt which can be supplied of any requisite length to fit the structure to which the anchor is attached. As these bolts are standard articles it is simply necessary in order to attain the advantages herein outlined to provide the anchor in the design illustrated and which can be conveniently formed as a casting together with a proper length carriage bolt. In this way, an anchor can be provided which can be accommodated to fit any size frame.

The concaved curved inner side 35 of the post as it merges into the plane containing the flanges 25, 26 facilitates a quick engagement of the post by the usual attaching clip forming part of the window cleaner's safety harness and thus ease and positiveness of a quick engagement is asserted by the forwardly projecting disposition of the post head to the outside of and beyond the planes of the adjacent attaching parts, defined by the surfaces 18 and 27.

I claim:

1. In a device of the class described, the combination of a building construction comprising a plurality of structural parts and provided with angularly disposed faces co-acting to form an exposed angle, a one-piece window-cleaner's safety anchor fashioned to fit said angle, said anchor comprising a main plate fitted to one of said faces, provided with a non-circular bolt hole extending therethrough and with a face-flange integral with an edge of said main plate and fitted to the other face, a post integral with said main plate and projecting therefrom at the edge provided with the face flange, said flange provided with a screw hole, a screw extending therethrough and into said other face, and a relatively long bolt having a non-circular head portion fitted in said bolt hole and held thereby from rotary movement when the bolt nut is turned on the opposite end, said bolt being offset from said screw, passed through said structural parts and acting as the primary means for securely fastening the anchor to the construction and said bolt also providing means for assisting in securing the structural parts in place and to defeat any tendency of abnormal strain on the post from separating the structural parts from each other.

2. In a device of the class described, the combination of a building construction comprising a plurality of structural parts and provided with angularly disposed faces co-acting to form an angle, a one-piece window-cleaner's safety anchor fashioned to fit said angle, said anchor comprising a main plate

fitted to one of said faces, provided with a bolt hole extending therethrough and with a face flange integral with an edge of said main plate and fitted to the other face, a post integral with said main plate and projecting therefrom at the edge provided with the face flange, said flange provided with a screw hole, a screw extending therethrough and into said other face, and a relatively long bolt passed through said bolt hole, said bolt being offset from said screw, passed through said construction fastening the anchor to the construction and said bolt also providing means for assisting in securing the structural parts in place and to defeat any tendency of abnormal strain on the post from separating the structural parts from each other.

3. In a device of the class described, the combination of a support providing a main face and another face extending at an angle to the main face, an anchor including a main element fitted to said main face and a facing element extending integrally from one edge of the main element and fitted to said other face, a single bolt extending through the main element and into said main face and said facing element in its engagement with said other face acting to prevent rotation of the main element about said single bolt and said main element provided with a headed post extending integrally therefrom and projecting beyond the planes containing said main and facing elements.

Signed at New York city in the county of New York and State of New York, this 8th day of January, A. D. 1930.

AINSWORTH BUCK.
